UNITED STATES PATENT OFFICE.

ABRAM P. BROWN, OF HARTFORD, CONNECTICUT.

DESIGN FOR A SPOON.

SPECIFICATION forming part of Design No. 24,297, dated May 14, 1895.

Application filed December 18, 1894. Serial No. 532,261. Term of patent 14 years.

To all whom it may concern:

Be it known that I, ABRAM P. BROWN, a citizen of the United States, residing at Hartford, in the county of Hartford and State of Connecticut, have invented and produced a new and original Design for Spoons, of which the following is a specification, reference being had to the accompanying drawings.

Figure 1 is a plan view of a spoon, showing my design. Fig. 2 is a vertical central section through the bowl in the plan shown by the dotted line. Fig. 3 is a side elevation of the spoon.

The leading feature of my design consists of the contour of the bowl and particularly in the position of the handle and in the position and shape of the nose or point.

A represents the handle, B the bowl, and C the nose of the spoon. The outline of the bowl extends from the point 3 in an elliptical curve to the point 4, then in a circular arc to the point 5, then resuming the elliptical form to the point 6, concave to 7, convex to the point of the nose 8. From 8 the outline is convex to 9 where it is concave to 10 joining the elliptical curve to 2. At—11—11 are two

ribs or folds which mark the division between the bowl proper and the nose.

The outline of the handle which joins the bowl in the center of the elliptical curve 30—10—4—is concave from points 2—3 to 12—12, thence gradually contracting as it extends upward to the points 13—13 its narrowest point, then expanding to 14—14, from which point each side rounds to the end 15. 35

In Fig. 2 the outline of the bottom of the spoon is circular from 10 to 17 where the bottom of the spoon joins it, being tangent to it at that point.

In Fig. 3 the outline of the bottom is circular as shown from 19 to 20. The handle extends upward from 20 to 21 in a well defined curve, then nearly straight to 22 where it curves slightly in the reverse direction to the end 23. 40

What I claim is—

The design for a spoon as herein shown and described.

ABRAM P. BROWN.
